DIRECTIONAL MICROWAVE TRANSMISSION
SYSTEM HAVING DIELECTRIC LENSHenry E. De Vore, Cranbury, N. J., assignor to
Radio Corporation of America, a corporation
of Delaware

Application August 20, 1945, Serial No. 611,649

2 Claims. (Cl. 178—44)

1

This invention relates generally to microwave transmission and more particularly to a method of and means for proportioning a dielectric element disposed between conductive elements to minimize reflections of microwaves propagated between said conductive elements.

Frequently radiating systems for microwave electromagnetic radiation utilize solid dielectric elements disposed between metallic conductive elements. For example, the dielectric element may be in the form of a lens between parallel metal sheets employed to focus the microwave radiation, or the dielectric element may comprise a mechanical support for the metallic conducting members. It is often desirable that the microwave transmission characteristic be substantially uniform throughout the region occupied by the dielectric element.

In wave guides or microwave transmission systems containing parallel disposed conductive plates, non-uniform microwave transmission characteristics are produced by the existence of an air gap of varying thickness between the surface of the dielectric and the adjacent metal surface. While this difficulty, in some instances, may be avoided by bonding the metal surface to the dielectric surface, such bonds are difficult to obtain and are not always feasible in the particular mechanical structure desired. However, it is customary to apply to the surface of the dielectric element facing the metal surface a thin metallic coating which provides for uniform transmission of the radiation in the region adjacent to the dielectric. A small portion of the incident radiant energy will be propagated through the air gap between the coated dielectric element and the surface of the metallic element. Microwave transmission through this air gap may cause interference with the microwaves propagated through the dielectric element, thereby providing undesirable reflections in the transmission system. Also it is essential that the dielectric element be so proportioned that internal reflections of incident microwaves therein substantially cancel external surface reflections therefrom.

Among the objects of the instant invention are to provide an improved method of and means for minimizing wave reflections in a microwave transmission system which includes a solid dielectric element. Another object is to provide an improved method of and means for proportioning a solid dielectric element in a microwave guide for minimizing wave reflections and wave interference due to the presence of said dielectric element in said guide. An additional object of

2

the invention is to provide an improved microwave focusing element in a wave transmission system. Another object is to provide a substantially reflectionless solid dielectric element disposed within a microwave transmission guide. A further object is to provide an improved method of and means for proportioning a dielectric element in a microwave guide system to minimize surface reflections from said dielectric element as well as wave interference between waves propagated through said element and waves propagated around said element.

The invention will be described in greater detail by referring to the accompanying drawing of which Figure 1 is an elevational cross-sectional view of a first embodiment of the invention, Figure 2 is a plan cross-sectional view taken along the section line II—II of a second embodiment of the invention, Figure 3 is an elevational cross-sectional view taken along the section line III—III of said second embodiment of the invention and Fig. 4 is a perspective view thereof. Similar reference characters are applied to similar elements throughout the drawing.

Referring to the drawing, Figure 1 shows a wave guide 1 having microwaves propagated therethrough in the direction indicated by the arrow 3. A dielectric element 5, having metallic surface coatings 7 and 9 disposed on the surfaces thereof adjacent to the inner walls of the wave guide 1, is proportioned to have a length L of a critical value for minimizing surface reflections of incident microwaves and interference between microwaves transmitted through the dielectric element and microwaves transmitted through the gap between the wave guide 1 and the conductive coatings 7 and 9.

It is known that the wave energy reflected by a dielectric element will be minimized if the thickness of the element in the direction of wave propagation is an integral number of half wavelengths of the electromagnetic radiation, as measured in the particular dielectric material. For a dielectric element of such length, the internal microwave radiation reflected by the back face 11 re-emerges from the front face 13 in exactly opposite phase to the external radiation reflected by the front face 13. Thus the two wave reflection components produce destructive wave interference and tend to cancel, with the result that minimum radiation is reflected back toward the source of wave radiation.

It is also desirable to eliminate, insofar as possible, the disturbing effects caused by wave radiation which travels through the small wave gaps

between the coated surfaces 7 and 9 of the dielectric and the inner surface of the wave guide 1. If the radiation travelling through these air gaps does not emerge therefrom in phase with the wave radiation which travels directly through the dielectric element 5, destructive interference between the fields of said radiation will occur, with the result that the wave radiation propagated beyond the dielectric element will be reduced in intensity and part of such radiation will be reflected back toward the source of wave energy.

In order to reduce such reflections, the length L of the dielectric element 5 is selected effectively to cancel internal and external wave reflections in the dielectric element as well as to provide a minimum of wave interference between waves propagated through the dielectric element and waves propagated through the air gap between said element and the inner surface of the wave guide. If the dielectric element has a dielectric constant k , and the wave length of the radiation in air is λ , the wave length in the dielectric will be

$$\frac{\lambda}{\sqrt{k}}$$

In order to satisfy the condition for minimum wave reflection from the dielectric faces 11 and 13, the length of the dielectric element should be

$$L = \frac{n\lambda}{2\sqrt{k}} \quad (1)$$

where n is an integer.

In the air gap, the radiation requires

$$\frac{L}{\lambda}$$

periods to traverse the distance L , while in the dielectric the time required will be

$$\frac{L\sqrt{k}}{\lambda}$$

periods. In order to avoid destructive interference between radiation travelling through the air gaps and that travelling through the dielectric element, the difference in propagation time should be an integral number of periods, such that

$$\frac{L\sqrt{k}}{\lambda} - \frac{L}{\lambda} = m.$$

or

$$L = \frac{m\lambda}{\sqrt{k} - 1} \quad (2)$$

where m is an integer.

The optimum condition to satisfy both Equations (1) and (2) is realized by combining the equations whereby

$$\frac{n}{m} = \frac{2\sqrt{k}}{\sqrt{k} - 1} \quad (3)$$

where n and m both are integers, and where k also is the ratio of the dielectric constants of the two dielectrics, since the dielectric constant of air is substantially unity. For most dielectric materials, the quantity

$$\frac{2\sqrt{k}}{\sqrt{k} - 1}$$

may not be accurately expressed as the ratio of two reasonably small integers, and hence both types of reflection phenomena may not be completely eliminated by utilizing dielectric elements having reasonably short lengths. However, in

general, the radiation reflections from the dielectric faces are large compared with the reflections due to phase interference of waves propagated through the air gaps, providing the air gaps are held to reasonably small dimensions. Therefore, it is desirable to choose a length for the dielectric element such that the condition represented by the Equation (1) is accurately satisfied and the condition represented by the Equation (2) is approximately satisfied.

As an illustration, the following calculations indicate the shortest length L of a polystyrene dielectric element which will provide minimum reflection for radiation of 0.5" in wave length. For this radiation the dielectric constant of polystyrene is 2.56. Hence substituting in Equation (1)

$$L = \frac{n \times 0.50}{2\sqrt{2.56}} = n \times 0.156 \text{ inch} \quad (4)$$

also substituting in Equation (2)

$$L = \frac{m \times 0.50}{\sqrt{2.56 - 1}} = m \times 0.833 \text{ inch} \quad (5)$$

Hence it is seen that the optimum length for the polystyrene element are those multiples of .156" which occur closest to multiples of .833". The values for $n=16$ and $m=3$ almost precisely satisfy both equations. However, a dielectric element having a length of approximately 2.497", while providing extremely low reflections, may introduce too much attenuation under some conditions. In the latter instance lower values must be selected for the integers m and n .

In a more general case, let k_2 =dielectric constant of the dielectric block, k_1 =dielectric constant of the surrounding medium wherein both are relative to air (or vacuum), hence the wavelength in the dielectric block is

$$\lambda_2 = \frac{\lambda_0}{\sqrt{k_2}}$$

where λ_0 is the wavelength in air (or vacuum). In order that reflections from front and back block surfaces cancel, since there is a phase reversal at one reflective surface and not at the other, the block length must be an integral number of half wavelengths of the radiation (measured in the block). Hence:

$$L = \frac{n\lambda_2}{2} = \frac{n\lambda_0}{2\sqrt{k_2}}$$

or

$$n = \frac{2L\sqrt{k_2}}{\lambda_0} = 2\sqrt{k_2} \frac{L}{\lambda_0}$$

In the gap, the number of periods required to propagate a distance L is

$$\frac{L}{\lambda_1}$$

or

$$\frac{L}{\lambda_0\sqrt{k_1}}$$

where λ_1 is the wavelength in the fluid medium and k_1 its dielectric constant. The number of periods required to propagate through the block is

$$\frac{L}{\lambda_2} = \frac{L}{\lambda_0} \sqrt{k_2}$$

In order to have no interference, the difference of these two numbers of periods must be an integer:

$$\frac{L}{\lambda_0\sqrt{k_2}} - \frac{L}{\lambda_0\sqrt{k_1}} = m = \frac{L}{\lambda_0} (\sqrt{k_2} - \sqrt{k_1})$$

combining, if both conditions are satisfied:

$$\frac{n}{m} = \frac{2\sqrt{k_2}}{\sqrt{k_2} - \sqrt{k_1}} = \frac{2\sqrt{\frac{k_2}{k_1}}}{\sqrt{\frac{k_2}{k_1}} - 1} = \frac{2\sqrt{k'}}{\sqrt{k'} - 1}$$

where k' is the ratio of the dielectric constants.

Referring to Figures 2 and 3, the principles of the instant invention are applied to the design of a corrective dielectric lens employed in cooperation with a microwave reflector whereby undesirable reflections from the lens surfaces are minimized. While the thickness of the lens varies throughout its width, there is a comparatively wide region near the center of the lens throughout which the thickness is relatively constant. Since a proportionally large fraction of the radiation is directed through the central region of the lens, proportioning the lens thickness in the central region to values which approximately satisfy Equations (1) and (2) eliminates a large proportion of the undesirable wave reflections from the lens surfaces.

In Figures 2 and 3 a microwave generator 21 is coupled through a wave guide 23 to a point 25 at the focus of a toroidal wave reflector 27. The waves radiated by the wave guide 23 are guided to the reflector 27 between parallel disposed conductive plates 29 and 31. The incident waves from the wave guide 23 pass through a dielectric corrective lens 33, are reflected by the metallic reflector 27 and pass to the output wave path 35, which is in a plane displaced with respect to the plane of the waveguide 23 and corrective lens 33. Preferably, the corrective lens 33 has conductive coatings 37 and 39 on the upper and lower surfaces thereof in close proximity to the inner surfaces to the conductive plates 29 and 31, respectively, thereby providing air gaps 41 and 43 of the same type as described heretofore with respect to the device of Figure 1. Side conductive elements 45 and 47 are optional and are employed merely to prevent wave leakage between the edges of the conductive plates 29 and 31, and to provide supporting elements for said plates.

It should be understood that the use of the conductive coatings on the surface on the dielectric element adjacent to the inner surface of

the wave guiding means is optional. However, in general, the use of such conductive coatings on the dielectric element provides a more uniform leakage path through the air gap between the dielectric element and the inner surface of the wave guiding means, the reflection effects of which may be more effectively neutralized by proper proportioning of the length of the dielectric element.

10 Thus the invention disclosed comprises an improved method of and means for reducing reflections in a wave guiding system due to the presence of a solid dielectric element by suitably proportioning the length of said dielectric element to neutralize surface reflections therefrom and effectively to minimize wave interference between waves propagated through said element and waves propagated through the spaces surrounding said element.

20 I claim as my invention:

1. In a microwave dielectric guide having a first dielectric with a dielectric constant k_1 , a substantially reflectionless second dielectric lens element having a dielectric constant k_2 disposed 25 transversely within said guide, said element having a length

$$L = \frac{n\lambda_0}{2\sqrt{k_2}} = \frac{m\lambda_0}{\sqrt{k_2} - \sqrt{k_1}}$$

30 along the axis of wave propagation, where λ_0 is the wavelength in air or vacuum, and n and m are integers.

2. A device according to claim 1 including conductive means on the surfaces of said element adjacent to the inner surfaces of said guide.
